UNITED STATES PATENT OFFICE.

NOAH E. LUCAS, OF NORWICH, CONNECTICUT.

UNDER CLEARER ROLL.

Application filed December 12, 1923. Serial No. 690,081.

To all whom it may concern:

Be it known that I, NOAH E. LUCAS, a citizen of the United States, and a resident of Norwich, in the county of New London and State of Connecticut, have invented new and Improved Under Clearer Rolls, of which the following is a specification.

My invention relates to the class of devices that are used in connection with the front, 10 bottom drawing rolls in spinning frames, mules, etc., in the manufacture of various textiles, such as cotton, woolen, silk, etc., for catching and winding up broken threads, lint and other waste for the purpose of keeping said bottom drawing roll clean, and an 15 object of my invention, among others, is to provide an under-clearer roll that will effectually catch and pick up broken ends and thereby remove them from space surrounding the machine and consequently eliminate 20 any danger of such ends catching upon other parts of the machine or upon material used in the spinning or other operations; and a further object of my invention is to provide 25 an under-clearer roll from which the material collected thereon may be readily removed with little trouble and loss of time and without injury to said roll.

One form of under-clearer roll embodying 30 my invention and in the construction and use of which the objects herein set out, as well as others, may be attained, is illustrated in the accompanying drawings, in which—

35 Figure 1 is a diagrammatic view illustrating a pair of drawing rolls and the operative relation of my improved under-clearer roll with respect thereto.

Figure 2 is a side view, scale enlarged, of 40 my improved under-clearer roll with one end broken away to show its construction, and with a portion of the roll intermediate its ends broken out.

Figure 3 is a view in cross section through 45 my improved roll, on a plane denoted by the dotted line 3—3 of Figure 2.

Figure 4 is a side view of the roll.

Figure 5 is a detail view showing another form of journal.

50 In that application of my improved roll illustrated in Figure 1, but which is to be taken in no way in a restricted sense, said roll 5 is rotatably mounted in contact with the under side of a fluted drawing roll 6 of a 55 well known arrangement of rolls employed in spinning and similar machines, this roll

6 being mounted in cooperative relation with an upper roll 7, between which rolls 6 and 7 yarn or strands 8 pass and by the operation of which rolls such yarn or strands are 60 drawn and evened.

My improved under-clearer roll 5 is constructed in a manner hereinafter described to promptly and effectually catch up the 65 ends of all strands that may be broken and thus remove them from space surrounding the machine by causing them to adhere closely to the roll, such roll accumulating material, including such broken ends, in a manner to permit the accumulated mass to be read- 70

75 My improved under-clearer roll consists of a body 9, that is composed of any suitable material, preferably cork, that is compacted in any suitable manner and that has a groove 10 extending in a spiral direction along said body. This groove is filled with a material, preferably that may be packed into the groove and that will have the properties for catching loose threads, lint and the 80 like. Felt has been found to satisfactorily answer this purpose, but it is contemplated that any other material having these characteristics may be employed. This filling 85

11, which I term a catcher, is preferably flush with the outside surface of the body 9. A plate 12 is secured to each end of the roll, each plate having a journal 13 projecting therefrom. A cap 14 preferably of non-metallic material, is secured to cover the 90 plate 12, in the preferred form of construction the bearing 13 being threaded for threaded engagement with a hole in the cap. These parts may be secured in place 95 on the end of the body in any desired manner, screws 15 effectively answering this purpose.

A roll constructed as above described will effect very satisfactory results, but for various reasons and under some conditions of use, I have found that a metallic covering for the roll will produce advantageous results. To this end I envelop the body 9 with a sleeve 16, preferably of metal, this sleeve having a slot 17 registering with the groove 10 and through which the filling material or catcher 11 may project, when such sleeve is used the filling preferably being flush with the outer surface of such sleeve.

As a further aid in catching up the 110 threads and lint, I provide a spiral groove 18, shown herein as formed in the sleeve 16,

but when the sleeve 16 is omitted this groove may be formed in the outer surface of the body 9. This groove is formed with a shoulder 19 along one edge and it tapers 5 gradually from said shoulder to the outer surface of the sleeve. I have found that this shoulder is a material aid in effecting the collection of loose threads, lint and the like.

When the sleeve 16 is employed it is projected slightly beyond the body and its open end is threaded to receive the threaded edge of the plate 12, as shown in Figure 2 of the drawings.

While I have shown and described herein 15 my improved roll in one form as embodying an enveloping metallic sleeve having a slot through which the catcher projects from the groove within the body of the roll, I contemplate as within the spirit and intent of 20 of the invention a structure in which said sleeve may be otherwise formed to receive or support the filling material or catcher, and it will, therefore, be understood, as contemplated within my invention, any roll having 25 a spirally formed groove in its outer surface containing the filling material or catcher, whether such be formed in the outer surface of the roll, of whatsoever material, or whether it be formed in a body so that the 30 filling material will project through a slot in a sleeve enveloping said body.

In the construction shown in Figure 5 the journal is extended entirely through the roll, the plate 12 having a hole 20 through which 35 the journal extends, the journal 13 in fact being integral with a rod 21, and the latter being secured at both ends in the same manner as shown at the one end in this figure.

In accordance with the provisions of the 40 patent statutes I have described the principles of operation of my invention, together with the device which I now consider to represent the best embodiment thereof; but I desire to have it understood that the device shown is only illustrative and that the 45 invention may be carried out by other means and applied to uses other than those above set out.

I claim—

50 1. An under-clearer roll having a groove extending in a spiral direction from end to end of the roll, said groove having a single shoulder located at one side thereof and facing in the direction of rotation of the 55 roll, and journals formed at the ends of said roll.

2. An under-clearer roll having a groove extending in a spiral direction from end to end of the roll, said groove having a single shoulder located at one side thereof. 60

3. An under-clearer roll having an outer surface of smooth, polished metal with a spiral groove therein, and a catcher comprising material having an affinity for lint, threads etc., located in said groove and comprising a comparatively small portion of the outer surface of the roll and with the outer surface of the catcher being substantially flush with the outer surface of the roll. 65

4. An under-clearer roll comprising a 70 body having a groove in its surface, an enveloping sleeve having a slot registering with said groove, and a catcher comprising material having an affinity for lint, threads etc., located in said groove. 75

5. An under-clearer roll adapted to catch up lint, threads, etc., comprising a body, a sleeve enveloping said body, a plate with a journal extending therefrom secured to said body, and a cap covering said plate. 80

6. An under-clearer roll adapted to catch up lint, threads, etc., comprising a body, a sleeve enveloping said body, a plate secured to said body and having a journal extending therefrom, and a cap of non-metallic material secured to cover said plate. 85

7. An under-clearer roll comprising a body having a spirally arranged groove, a metallic sleeve enveloping said body and having a slot registering with said groove, a catcher comprising material having an affinity for threads, lint etc., located in said groove, a plate secured to said body and having a journal projecting therefrom, and a cap of non-metallic material secured to 90 cover said plate. 95

8. An underclearer roll comprising a member having a slot in its wall, said slot being open at the top and bottom and a catcher comprising material having an affinity for lint, threads, etc., located within said member and projecting through said slot to the outer surface of said member, and means for supporting said member. 100

9. An underclearer roll having a smooth polished surface with a spiral groove therein, and a catcher comprising material having an affinity for lint, threads, etc., located in said groove with the outer surface of the catcher substantially flush with the outer 105 surface of said roll. 110

NOAH E. LUCAS.
